DESIGN FOR WALL-PAPER.

SPECIFICATION forming part of Design No. 26,095, dated September 22, 1896.

Application filed August 5, 1896. Serial No. 601,830. Term of patent 3½ years.

To all whom it may concern:

Be it known that I, CHARLES Booz, a citizen of the United States, residing at Buffalo, in the county of Erie and State of New York, have invented and produced a new and original Design for Wall-Paper, of which the following is a specification, reference being had to the accompanying drawing, showing a part thereof.

10 The design consists of a series of connected circles formed of ribbons and arranged in vertical rows with small wreath-like ornaments and small fleur-de-lis-shaped ornaments in the center of said wreaths and inclosed in 15 said circles, and small palm-like ornaments also inclosed in said circles, and rows of vertical lines between the rows of circles, as represented in the accompanying drawing.

The border for the said design is formed

of ribbons arranged in the form of a row of 20 circles, in which are placed wreath-like ornaments with a small fleur-de-lis ornament in the center, and above said ribbons is arranged a row of open wreaths, and below said ribbons is arranged an ornamental band, forming the bottom of the border, as shown in the drawing.

What I claim is—

1. The design for wall-paper herein shown and described. 30
2. In the design for wall-paper the border herein shown and described.

Witness my hand this 1st day of August, 1896.
